UNITED STATES PATENT OFFICE.

FREDERICK DANIEL ALTHAUSE, OF NEW YORK, N. Y.

MULTITUBULAR STEAM-BOILER.

SPECIFICATION forming part of Letters Patent No. 694,048, dated February 25, 1902.

Application filed October 11, 1901. Serial No. 78,298. (No model.)

To all whom it may concern:

Be it known that I, FREDERICK DANIEL ALTHAUSE, a citizen of the United States, and a resident of the borough of Bronx, in the city 5 and State of New York, have invented a new and useful Improvement in Multitubular Steam-Boilers, of which the following is a specification.

This invention relates to multitubular boilers of the water-tube kind, and especially to such boilers made in separable sections; and it consists in certain details of construction and certain combinations hereinafter described and claimed whereby I obtain a boiler 15 of great steam-generating capacity in proportion to its size and weight which is easily cleaned, repaired, and kept in order and easily set up and of which the sections are conveniently transportable.

Figure 1 represents a vertical section transverse to its tubes of a sectional water-tube boiler embodying my invention; Fig. 2, a vertical section of the same parallel with the tubes; Fig. 3, an elevation of one of the hollow slabs or boxes of which, with the tubes and steam-drum, the boiler is composed, the outer portion being omitted to show its interior; Fig. 3*, a horizontal section of a complete slab or box; Fig. 4, a view corresponding with 30 Fig. 3, showing the connection and communication between two of said slabs on one side of the boiler; Fig. 5, a horizontal section of the rear part of the boiler; Figs. 6 and 7, respectively a front and a rear view illustrating 35 the tube connections.

A A designate upright hollow slabs or, as they will be hereinafter termed, "boxes," of which the sides of the boiler are composed. B, B', and B* are tubes arranged transversely 40 to said boxes and connecting every two opposite ones and forming such communications between them that two boxes and their connecting-tubes constitute one section of the boiler.

C is a steam-drum, with which the upper parts of the several boxes are connected by pipes D D. The several sections, of which there may be any number, constituted as above mentioned and forming both water and 45 steam spaces are erected closed together, as shown in Fig. 1, on any suitable setting—such, for example, as the cast-iron base E rep-

resented. To complete the boiler thus composed of sections, walls F and G are erected in front and rear of the series of sections. A 55 roof I or crown-plate with a chimney I' is placed over the said sections and end walls, and a grate H is provided in the lower part of the space between said sections and rear walls, a fire-door J above the grate and ash-pit door 60 K below the grate being provided in the front wall F. The walls F and G may be of any suitable material or construction. They are represented as composed of double plates g h, 65 spaced by intermediate frames i and having their spaces filled with asbestos j, and they are shown as bolted to the end boxes A by bolts k.

No tubes are provided between the lower parts of the boxes A A over the grate H except those B' at the back of the rear section, the omission of the tubes leaving sufficient space over the grate to form a fire-chamber of suitable capacity and the tubes B' occupying or forming the rear portion of the fire-chamber. The tubes B B' of alternate rows have a slant in opposite directions for the purpose of providing for an active upward circulation of water and steam between the opposite boxes A of each section. The circulation-tubes B* below the grate are represented as without slant. The boxes of the two end sections are braced together laterally by brace-rods L, screw-threaded at their ends and fitted with nuts d d.

The construction of the boxes A A for obtaining easy access to the tubes, which is an important feature of the invention, is particularly illustrated in Figs. 2, 3, 3*, and 4. Each of said boxes consists of an inner plate 90 or tube-sheet a, having in it a cavity constituting a water and steam space formed by a flange a' around its margin and an outer plate a², bolted to said flange by bolts a³, screwed into tapped holes a⁴ in said flange. 95 The plates a a² are stayed together by headed stay-bolts a⁵, screwed into tapped holes a⁷ in bosses a⁶, which are formed on the inner face of the plate a integral therewith and project therefrom nearly flush with the flanges a', so that the said plate a² fits so close to both said flanges and bosses as just to leave 100 room between them for a suitable packing, as asbestos. The stay-bolts thus applied and

not projecting through the inner plates α of the boxes A are unexposed both to fire and to water and thus not liable to corrosion, and if injured in any way they can be replaced 5 from outside the boiler without removing anything else.

To provide communication between the abutting boxes of two adjacent sections, matching apertures b are provided, as shown 10 particularly in Fig. 4, so that water and steam may circulate freely between the sections. The adjacent boxes are bolted together by screw-bolts c , which pass through their flanges α' , tight joints being made between the contiguous flanges by any suitable packing. These bolts c have to be inserted before the plates α^2 are put in place, 15 but are accessible at any time by removing said plates.

20 The grate H has its length formed, as shown in Fig. 1, of short bars of lengths corresponding with the several boiler-sections, the said bars for each section being supported on two transverse bearers e , which rest in projections f , provided on the inner faces of the boxes A, each boiler-section having its own grate or grate-section and being thus complete in itself, so that a boiler may be made up of any suitable number of such sections 25 30 properly connected, and its capacity may be at any time increased, if necessary, by the addition of another section.

In the boiler thus constructed while the tubes are to a very considerable extent exposed to the radiant heat of the incandescent fuel in the fire-chamber and the heated gaseous products of combustion circulate between them on their way to the chimney I' the water and steam are in active circulation 35 40 to and fro through the tubes between the opposite boxes of each section and between the adjacent boxes of the several sections, and hence by reason of this active circulation and the extensive heating-surface afforded by the 45 tubes being made of small caliber and very numerous a boiler of great steam-producing capacity and power may be made of comparatively very light weight and if divided into a suitable number of sections may be very 50 portable.

In the construction of the boiler it is obvious that the tubes B B' B* must be inserted into the plates or tube-sheets α before the plates α^2 are applied to the latter. The ends 55 of the tubes are, as shown in Fig. 7, received in outwardly-tapered holes in said plate α and may first be expanded therein in the usual way to some extent by any suitable expander; but they are further expanded and tightened 60 therein by screwing into each expanded end a taper externally-screw-threaded bushing l , which is of a length somewhat greater than

the thickness of the plate, and therefore so made to project beyond the faces of the plate as to reinforce the tube. The screw-threaded 65 bushing being made of steel of a quality harder than the tubes may cut its own screw-threaded way into the tube. The said bushings may be easily removed by unscrewing them for the repair of the tubes. To permit 70 this it is of course necessary to take off the plate α^2 from the box. On the removal of these plates α^2 of two opposite boxes A all the tubes of that box may be examined and easily cleaned.

What I claim as my invention is—

1. A section of a water-tube boiler consisting of two opposite upright boxes and communicating transversely-arranged tubes, the said boxes being each composed of an inner 80 plate constituting a tube-sheet and an outer plate separable from said inner plate for access to the tubes, substantially as herein described.

2. The combination with the inner and 85 outer plates of a water-box for a boiler, of bosses which are formed upon the inner plate integral therewith and stay-bolts passing through the outer plate from its exterior and screwed into said bosses, substantially as herein described.

3. The combination in a water-tube boiler of two or more water-boxes abutting together and each composed of a flanged inner plate constituting a tube-sheet and an outer plate 95 detachably secured to the flange of said inner plate, and bolts securing said boxes together through the flanges of their inner plates, the said flanges having in them openings for communication between the abutting boxes, substantially as herein described.

4. The combination in a water-tube boiler composed of two or more sections each consisting of two opposite boxes and transverse connecting-tubes, of a fire-grate made in sections one for each boiler-section, and means for supporting said grate-sections independently each on its own boiler-section, substantially as herein described.

5. The combination with the tube-sheet of 100 a boiler having a taper hole for the reception of a tube, of a tube inserted within said hole and a taper externally-threaded expanding-bushing screwed into said tube within the tube-sheet, substantially as herein described. 115

In testimony that I claim the foregoing as my invention I have signed my name, in presence of two witnesses, this 9th day of October, 1901.

FREDERICK DANIEL ALTHAUSE.
